SNOWMOBILE AMBULANCE BODY

David R. Haskins, Tomahawk, Wis., assignor to Lake Nokomis Enterprises, Inc., Tomahawk, Wis.

Filed Feb. 28, 1972, Ser. No. 230,181

Term of patent 14 years

Int. Cl. D12—14

U.S. Cl. D14—24

Fig. 1

Fig. 2

Fig. 3

Fig. 4

Fig. 5

Fig. 6

FIG. 1 is an isometric view of a snowmobile ambulance body embodying my new design;

FIG. 2 is a side elevational view thereof, the opposite side being identical;

FIG. 3 is a rear elevational view thereof;

FIG. 4 is a top plan view thereof;

FIG. 5 is a front elevational view thereof;

FIG. 6 is a bottom plan view thereof.

I claim:

The ornamental design for a snowmobile ambulance body, as shown and described.
